UNITED STATES PATENT OFFICE.

EDWARD J. FOWLER, OF SAN FRANCISCO, CALIFORNIA, ASSIGNOR TO GENERAL CHEMICAL COMPANY, OF NEW YORK, N. Y., A CORPORATION OF NEW YORK.

SHAFT FOR ROASTING-FURNACES.

1,100,426.

Specification of Letters Patent. Patented June 16, 1914.

Application filed March 24, 1913. Serial No. 756,318.

To all whom it may concern:

Be it known that I, EDWARD J. FOWLER, a citizen of the United States, and a resident of the city of San Francisco, county of San Francisco, and State of California, have invented a new and useful Improvement in Shafts for Roasting-Furnaces, of which the following, taken in connection with the accompanying drawings, is a specification.

10 My invention relates to roasting furnaces, especially such as are used for roasting ores, and such as are provided with stationary hearths upon which the ore is stirred and distributed by rakes or plows affixed to rotating arms, said arms being in turn affixed to and rotatable with a central vertical shaft which extends through central apertures in the hearths and is rotated by any suitable mechanism. A furnace of 20 such type is described and illustrated in the patent to John B. Francis Herreshoff, No. 976,175, dated November 22, 1910.

More particularly my invention relates to the central rotatable shafts of such furnaces, of the type in which the shaft is provided with an axial passage for conducting a cooling medium into passages of the rabble arms, and with an annular passage surrounding said axial passage, for conducting the medium from passages of the rabble arms to the exterior of the furnace, and the object of my invention is to produce a shaft of such kind which will be easy of manufacture and assembling or dismounting and will be free from other defects and disadvantages of shafts known before my invention, as, for instance, warping and buckling due to the intense heat to which such shafts are subjected.

40 Referring to the accompanying drawings illustrative of an embodiment of my invention, Figure 1 is an axial section through a portion of a sectional shaft constructed in accordance with my invention. Fig. 2 is a 45 plan view of one of the sections thereof, and Fig. 3 is a cross section along the line 3--3 of Fig. 1.

The shaft illustrated is composed of a suitable number of superposed sections of 50 which three only are shown in the drawings. Each section is secured at its ends to the adjacent sections by means of suitable fastening means such as the bolts 1 coöperating with the apertured abutting end flanges or 55 lugs 2 of the sections. The sections are gen-

erally of similar structure so that a description of one of them will be applicable to all. Each section is generally cylindrical in form. Concentric with the outer cylindrical wall 3 is an inner cylindrical wall 4, 60 these walls being held in separated relation by suitable means such as the radial ribs 5. The structure thus forms an axial passage 6 which is separated from and surrounded by an annular passage 7. At the places at 65 which, rabble arms are to be fastened to the arms, the outer wall is suitably conformed to coöperate with fastening devices for said arms, such conformations as shown including an outwardly projecting, flanged boss 8 70 which is provided with a passage 9 adapted to connect the annular space 7 with one of the passages of the coöperating hollow rabble arm and with a passage 10 which is continued by means of a suitable tubular construction 11 so as to connect the axial passage 6 with a passage of the rabble arm. 75

In the device shown the sections are articulated together in axial alignment, the outer walls 3 of adjacent sections abutting 80 each other at their ends whereby the annular passages 7 of the sections are in communication with each other. The bolts 1 coöperating with the flanges 2 of the sections insure a close contact between the sections 85 and prevent leakage. The inner walls of the sections align with each other so that the axial passages 6 of the sections communicate with each other without leakage and that at the same time the inner wall of each section 90 will be capable of expansion and contraction movements in a longitudinal direction independently of the inner wall of the other section. As shown the inner wall 4 is slightly longer than the outer wall 3, projecting beyond the end of the latter at one end of the section. This tubular projecting end 12 telescopes within the end 13 of the adjoining inner wall so that the walls are relatively movable longitudinally. 95

In the operation of the furnace a cooling medium, preferably air at ordinary temperature, is induced or forced through the axial passage 6 and the various passages 10 into the rabble arms; after traversing passages in the arms it is discharged therefrom through the passages 9 into the annular passage 7 from which it may escape into the atmosphere. In traversing the arms the air takes up heat therefrom, thus cooling the 105 110

2
 same, and the thus heated air is then conducted into the annular passage 7. It will readily be understood that the inner channel 6 of the shaft contains air at ordinary temperature, and the annular passage 7 contains air at a considerably higher temperature while the gases externally of the shaft have an extremely high temperature due to combustion upon the hearths of the furnace. 10 The temperature in the passage 6 may be 60° to 100° F. in the passage 7, 200° to 400° F. and externally of the shaft 1100° to 1600° F. It will be seen therefore that the inner wall 4 is of a much lower temperature than the outer wall 3; consequently in actual use of the furnace they will expand unequally. The 15 slidable joint 12-13 will permit such unequal expansion without injury of any kind to the shaft. The projection 12 beyond the plane of the outer face of the flange 2 at one end of each section acts as a centering guide for the portion 13 of the inner wall of the adjoining section, and, as will readily be understood, is of material aid in facilitating 20 the assembling of the sections to form a complete shaft.

I claim:

1. A shaft provided with an axial passage and an annular passage surrounding said 25 axial passage and separated therefrom by a cylindrical wall, said wall being composed of sections, said sections being connected by a

slidable joint, substantially as and for the purpose described.

2. A hollow shaft comprising outer and inner cylindrical walls and means for holding said walls spaced apart in concentric relation, said inner wall being composed of sections, said sections being connected by a 30 slidable joint, substantially as and for the purpose described.

3. A hollow shaft comprising articulated sections, each having outer and inner spaced walls, the outer walls of adjoining sections abutting each other and the inner walls 45 thereof being connected by a slidable joint, substantially as and for the purpose described.

4. A hollow shaft comprising articulated sections, each having concentrically arranged outer and inner cylindrical walls spaced apart and means for connecting the outer walls of adjoining sections together with the ends thereof abutting each other, the inner walls of said sections being connected by a telescopic joint. 50

In testimony whereof I have hereunto set my hand in the presence of two subscribing witnesses.

EDWARD J. FOWLER.
